UNITED STATES PATENT OFFICE

GEORGE L. PFANSTIEL, OF KANSAS CITY, MISSOURI

STRIPPER FOR DRUM BODIES

Application filed March 7, 1929. Serial No. 345,174.

- My invention relates to improvements in strippers for drum bodies, adapted particularly for use in stripping longitudinally slit large drum bodies, such as drums containing asphalt, or other solids, from the contents which adhere to the bodies. As heretofore practiced, the removal of the bodies of drums containing asphalt from the asphalt content has been effected with much difficulty and with the expenditure of considerable time and labor, due to the heavy strong material of such bodies, and to the tenacity with which the asphalt adhered to the inner sides of the bodies. Such removal of the bodies has generally been effected in a slow and tedious manner with the uses of axes and chisels, which was a slow process and which left the removed bodies in an expanded irregular form having sharp ragged edges, difficult to handle and requiring much storage or transportation space.
- One object of my invention is to provide a stripper of the kind described, which is simple, cheap, strong and durable, which is easily applied to a split drum body, and which when so applied to one longitudinal edge thereof, can be easily operated to wind the body thereon, thereby stripping the body from the contents of the drum, and which, when the body has been stripped from the contents, will leave the latter in a compact substantially cylindrical form convenient for storage or transportation, and readily detachable from the stripper. My invention provides further a novel and efficient method for the quick and easy removal of the bodies of large drums containing asphalt from the asphalt content, and the disposition of such removed bodies in compact form.
- The novel features of my invention are hereinafter fully described and claimed.
- In the accompanying drawing, which illustrates the preferred embodiment of my invention,
- Fig. 1 is a side elevation of my improved body stripper shown applied to one longitudinal edge portion of a longitudinal slit drum body.
- Fig. 2 is a top view of the same.
- Fig. 3 is a section on the line 3—3 of Fig. 2.

Fig. 4 is an enlarged fragmental cross sectional view showing the drum body partially stripped from the contents, the stripped portion being shown wound on the stripper arms.

Fig. 5 is a perspective view of the removable crank.

Fig. 6 is a top view of the stripper with the removable crank detached from the arms.

Fig. 7 is a reduced perspective view of a longitudinally slit drum body enclosing the contents, one longitudinal edge portion of the body being turned laterally outwardly, so as to be engaged by and between the arms of the stripper.

Similar characters of reference designate similar parts in the different views.

My improved body stripper comprises a device which is revoluble on its axis, and which is provided with means for holding a turned out longitudinal edge portion of a longitudinally slit drum body. Such holding means comprises, in the device illustrated, two parallel arms 1 and 2, held spaced apart by and fastened to, at one set of ends, a spacing plate 3.

To one end of the arm 1 is fastened a crank 4 by which the device may be revolved on its axis, to wind on the arms a longitudinally split body 5 of a drum.

6 designates another crank having a rectangular socket 7, which is adapted to releasably receive the free ends of the arms 1 and 2, for holding the arms operatively engaged with the body 5.

In the operation of the device, the drum body to be removed from the solid contents 8 of the drum, is first longitudinally slit from end to end, the drum head, not shown, having first been removed from the body. One longitudinal edge portion 9 of the body 5 is then bent laterally outwardly to form a longitudinal lip which is inserted between the arms 1 and 2. As shown in Figs. 1 and 2, the arms 1 and 2 are longer than the width of the body 5 with which they are adapted to be engaged, so that the free ends of the arms project outside the adjacent side edge of the body sufficiently to permit of the application to such free ends of the crank socket 7.

The removable crank 6 is then applied to

the arms, the latter being inserted in the socket 7, whereby the arms are held firmly engaged with the lip or edge portion 9. The cranks 4 and 6 are then revolved so as to 5 revolve the arms, thereby winding thereon the body 5, as shown in Fig. 4, and thus stripping the body from the asphalt 8, or other solid material, such as may form the contents of the drum.

10 After the body 5 is stripped from the contents 8, the crank 6 is removed from the arms 1 and 2, after which the arms are withdrawn from the roll, which has been formed by the wound body, by means of the crank 4.

15 It is usually a very difficult matter to remove the drum body from a drum of asphalt, due to the heavy material of the body and the adherence of the asphalt thereto. With the use of my improved stripper, this operation 20 may be very quickly and easily performed, and the body that has been stripped will be in compact form, easily transported and occupying small space.

I do not limit my invention to the structure 25 shown and described, as modifications, within the scope of the appended claims, may be made without departing from the spirit of my invention.

What I claim is:—

30 1. In means for stripping the body from the content of a relatively large asphalt containing drum, the heads thereof having been removed and said body slit for its full length, a device having means for engaging and holding 35 one of the slit edges of said body for the full length thereof, and having means for being revolved so as to wind thereon said body.

2. In means for stripping the body from 40 the content of a relatively large asphalt containing drum, the heads thereof having been removed and said body slit for its full length, a device having two arms adapted to receive between them and hold one of the slit edges 45 of said body for the full length thereof, and having means for holding and revolving said arms so as to wind thereon said body.

3. In means for stripping the body from 50 the content of a relatively large asphalt containing drum, the heads thereof having been removed and said body slit for its full length, a device having two arms adapted to receive between them and hold one of the slit edges 55 of said body for the full length thereof, said arms being adapted to project at both set of ends beyond said body, and two cranks, one attached to one set of ends of said arms, and the other removably attached to the other set of ends for revolving said arms so as to wind 60 thereon said body.

4. In means for stripping the body from 65 the content of a relatively large asphalt containing drum, the heads thereof having been removed and said body slit for its full length, 70 a device having two arms fastened together

at one set of ends, spacing means between said arms at said set of ends, a crank attached to said set of ends, and a removable crank removably mounted on the other set of ends of said arms and revoluble therewith, 75 said arms being adapted to receive between them and to hold one of the slit edges of said body for the full length thereof, so as to wind thereon said body when said arms are revolved by said cranks.

In testimony whereof I have signed my name to this specification.

GEORGE L. PFANSTIEL.
